FOREIGN PATENT DOCUMENTS

DE 202010016356 U1 3/2011

Primary Examiner — Jennifer L Rempfer(74) *Attorney, Agent, or Firm* — The Roy Gross Law Firm, LLC; Roy Gross(57) **CLAIM**

The ornamental design for golf towel, as shown and described.

DESCRIPTION

FIG. 1 is a front perspective view of a golf towel in accordance with the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The long dash broken lines of the carabiner form not part of the claim. The remaining broken lines represent surface features that form no part of the claim.

1 Claim, 4 Drawing Sheets(56)
